TRACK ASSEMBLY

Alexander Weber, Zollikofen, near Bern, Switzerland, assignor to Dr. Hans Beer, Bern, Switzerland, and Mrs. Emma Weber-Horisberger, trading as AWEPA, Zollikofen, near Bern, Switzerland

Filed May 18, 1959, Ser. No. 813,841

Claims priority, application Switzerland May 21, 1958
5 Claims. (Cl. 160—345)

The present invention relates to track assemblies.

More particularly, the present invention relates to that type of track assembly which is used for supporting draw curtains. For example, track assemblies of this type can be connected to a wall or ceiling so as to support draw curtains for movement to and from a position covering a window, doorway, etc. Of course, the track assemblies are not necessarily limited to a use with draw curtains and may have other uses.

Conventional track assemblies of this type have several disadvantages. Thus, it is extremely inconvenient to fix conventional track assemblies to a desired support surface. Where screw members extend through openings of the track structure into a wall or ceiling, the type of screw which can be used and the size thereof is limited by the size of the track, and also it is extremely difficult for one person to mount the track in a desired location. Thus, one person must hold a screw driver in one hand and with the other hand must hold not only the track itself but also the screw preparatory to applying the screw driver to the latter, and in addition to the difficulties involved in this operation it very frequently happens that the openings for the screws are not located at the desired positions which are convenient to the operator as well as those which are best adapted for the particular wall or ceiling.

One of the objects of the present invention is to overcome the above drawbacks by providing a track assembly of the above type which can very easily and conveniently be mounted at any desired location by a single person. Another object of the present invention is to provide a structure of the above type wherein, when the track is mounted at a desired location, the exterior of the track itself is visible and all fastening elements are hidden from view. Thus, in this way the fastening structure is protected by the structure against the possibility of injuring people or tearing fabric or the like with which the track may be associated.

It is also an object of the present invention to provide a track assembly of the above type which can be reliably connected to any desired part of a wall or ceiling extending in any desired direction therewith and having any desired arrangement of pull cords.

With the above objects in view the present invention includes in a track assembly of the above type, an elongated channel having an exterior track portion and a pair of opposed side wall portions which respectively terminate in free side edges which are adapted to be located adjacent a surface of a support to which the channel is to be connected with the hollow interior thereof directed toward the support surface. These side wall portions of the channel fixedly carry in the interior thereof fastening projections in the form of longitudinally extending flanges. A fastener means is turnably connected by the operator to the surface of the support prior to applying the channel thereto, and this rotary fastening means is provided with a pair of wings which are opposed to each other and which are adapted to engage the flanges at the surfaces of the latter which are directed away from the support surface so as to hold the channel against the support surface. With this arrangement the fastener means itself is for the most part housed within the channel and of course the flanges which cooperate with the fastener

means are also located within the channels and there are no exterior fastening elements which can be engaged so as to injure any person or object, for example, and also with this arrangement the operator first connects the fastener means to the support surface so that the channel 5 can then be very easily and quickly fastened thereto.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

FIG. 1 is a transverse, sectional elevational view 10 through a track assembly according to the present invention showing the latter connected to a support;

FIG. 2 is a top plan view of the structure of FIG. 1, FIG. 2 showing the structure as it appears when looking 15 downwardly on the structure from the support surface;

20 FIG. 3 is a side view of a fastener element according to the present invention;

FIG. 4 is an end view of a fastener element according 25 to the present invention;

FIG. 5 is a top plan view of a structure as it appears 30 when looking toward the interior of the channel of the invention, FIG. 5 showing how an extension strip cooperates with the channel;

FIG. 6 is a transverse sectional illustration of the 35 cooperation between a channel and extension strip of track assembly of the invention;

FIG. 7 is a transverse sectional view illustrating the 40 structure of a unit which includes a roll for guiding a pull cord;

FIG. 8 shows the arrangement of pull cord units according to the present invention;

FIG. 9 is a transverse sectional view of another embodiment of a channel according to the present invention; and

45 FIG. 10 is a top plan view of the structure of FIG. 9 showing how part of this structure may be cut away for a purpose described below.

Referring now to FIG. 1, the track assembly illustrated 50 therein includes an elongated channel 1 which may be made of any suitable metal or plastic which can be extruded through a suitable die so as to have the configuration illustrated in FIG. 1. The channel 1 is provided with an exterior substantially central track portion 1a in which any suitable slide member is guided for longitudinal movement along the track portion 1a of the channel 1, such a slide member being conventional and being connected to a curtain or the like so as to support the latter. At opposite sides of the track portion 1a the channel 1 is provided with the elongated grooves 7 which 55 are of substantially circular cross section and which serve to guide pull cords for movement longitudinally of the grooves 7, at least one of the pull cords being connected to the slide members which move along the track portion 1a so that by pulling on the pull cord the operator can 60 shift the slide members along the track portion 1a to adjust the curtains which are carried by such slide members, as is well known.

As may be seen from FIG. 1, the channel 1 is provided 65 with a pair of opposed side wall portions 5 and 6 which respectively terminate in free edges which are located, when the channel 1 is mounted for use, adjacent to the surface 2 of a support such as a wall or ceiling. Thus, it will be seen that the free edge 8 of the side wall portion 6 of the channel is located in direct engagement with the surface 2 of the support.

In accordance with the present invention channel 1 has fixedly connected to its side wall portions 5 and 6 in

the interior of the channel 1 projections in the form of longitudinally extending flanges 3 and 4 which serve as elements to cooperate with a fastener means described below. As is apparent from FIG. 1 the free edge portion 8 of the side wall 6 extends beyond the flange 4 while the flange 3 is located at the free edge of the opposite side wall portion 5 of the channel 1.

The structure of the invention includes one or more fastener means 9 which are adapted to be rotatably connected to the support at the surface 2 thereof. Each fastener means 9 is in the form of a substantially flat plate at least at its central portion 10. This central plate portion 10 of the fastener means 9 is formed with a bore through which a screw 11 passes into threaded engagement with the support so as to turnably connect the fastener means 9 to the support for turning movement around the screw 11. Each fastener means 9 includes a pair of opposed wing portions 12 which are diametrically opposed to each other and which are adapted to engage the flanges 3 and 4 at the sides of the latter which are directed away from the support surface 2, as is evident from FIG. 1, so that the fastener 9 serves in this way to fix the channel 1 to the support surface 2. The wing portions 12 of each fastener 9 respectively extend along a pair of helices and each fastener means 9 includes an elongated lever 13 shown most clearly in FIG. 2.

The plurality of fastener means are first fixed by screws 11 to the support at the surface 2 of the latter with the plurality of fastener means 9 spaced at any desired distance from each other and located along any desired path along which it is desired to place the channel or channels 1. After the user has mounted a plurality of fastener means 9 on the support, the plurality of fastener means 9 are placed in position shown at the right of FIG. 2. It will be noted that the wing portions 12 are of such a size that they will be freely located between the flanges 3 and 4 so that the latter can easily pass over the entire fastener means with the exception of the lever 13 thereof, this lever 13 extending between the flange 3 and the support surface 2 outwardly beyond the side wall 5, as is evident from the right portion of FIG. 2. It will be noted that the diameter of the plate portion 10 of the fastener means 9 is smaller than the distance between the fastening flanges 3 and 4.

Thus, with the plurality of the fastener means 9 in the position shown at the right of FIG. 2, the operator need only place the channel 1 against the surface 2, and then the operator can turn the several levers 13. These will be turned in a clockwise direction, as viewed in FIG. 2, so as to turn the levers 13 from the position shown at the right of FIG. 2 to the position shown at the left of FIG. 2. As a result the levers 13 will become located to a greater degree between the channel 1 and the surface 2 and the spiral wing portions 12 will engage the flanges 3 and 4 and will press against the latter so as to securely hold the channel 1 against the surface 2. The levers 13 can be turned up to the position indicated at the left of FIG. 2 so that the entire fastener means is located between the channel 1 and the surface 2 with the entire fastener means as well as the flanges 3 and 4 hidden from view and out of the way of any possible catching on fabric or on personnel so as to cause the undesirable injuries. The free end 14 of each lever 13 may be engaged with a screw driver, for example, when it is desired to remove the channel 1 from the supporting surface, and for this purpose an opening 15 may be provided at the free end portion 14 of each lever 13 so that a pin may be inserted into the opening 15 to facilitate turning of the lever 13, such a pin being insertable after the lever 13 has been turned to a position where the hole 15 is located beyond the side wall 5 of the channel.

As is apparent from FIG. 1, while the free side edge 8 of the side wall 6 is in direct engagement with the surface 2, the free edge of the side wall 5 is spaced from this surface but presses against the several levers 13 which are themselves in direct engagement with the surface 2.

The channels 1 of the track assemblies of the invention may be open at their ends, and an extension strip 16 having a configuration shown in FIGS. 5-7 may be introduced telescopically into the channel 1 through an open end of the latter. As is apparent from FIG. 6, the extension strip 16 engages the base of the channel 1 in the interior of the latter, and the width of the strip 16 is such that the side edge portions of the strip 16 engage the flanges 3 and 4 at the sides of the latter which are directed away from the surface 2. In this way the channel 1 and the strip 16 cooperate with each other in such a way that the channel 1 guides the strip 16 for longitudinal movement with respect to the latter, and this strip 16 has upwardly directed longitudinal portions which at their top surfaces are adapted to engage the surface 2 so as to be further guided for longitudinal movement in this way.

The strip 16 is adapted to carry a unit 17 which is provided with a guide roll 22 for guiding the pull cord. Thus, as may be seen from FIG. 7, a screw 24 is threadedly connected to the extension strip 16 at a part of the latter which is located beyond the channel 1, and this screw 24 passes through an axial bore of a tubular member 23 which is formed integral with the exterior plate portion of the unit 17, as is evident from FIG. 7. This tubular portion 23 turnably supports the guide roll 22 for the pull cord which is adapted to pass around the guide roll 22, and it will be seen that with this arrangement the downwardly directed surface of the extension strip 16, as viewed in FIG. 7, engages the top surface of the guide roll 22 to prevent axial movement of the latter on the sleeve 23. Thus, it is possible with the screw 24 to fix the unit 17 of FIG. 7 to the extension strip 16 to an end of the latter, the threaded opening of the strip 16 which receives the screw 24 being shown at the right of FIG. 5. With the unit 17 fixed to the strip 16 the latter may be moved longitudinally with respect to the channel 1 so as to locate the unit 17 at any desired position with respect to the channel 1.

FIG. 8 illustrates the arrangement shown in FIG. 5 in further detail. As can be seen from FIG. 8, an additional member 17 is fixed to the end of the extension strip 16 projecting beyond one end of the channel 1. The member 17 is substantially in the form of a cap abutting with an upper edge thereof against the support face to which the elongated channel 1 is connected and with a hollow stem 23 against the bottom surface of the extension strip 16. A screw 24 extends through the hollow stem 23 and is screwed in a correspondingly threaded opening in the extension strip 16 to fasten the member 17 to the extension strip. Turnably arranged about the stem 23 is a guide roll 22 having an axis extending substantially normal to the support surface. The member 17 is provided at a portion thereof extending beyond the extension strip 17 with a downwardly directed opening in which a sleeve 25 having an opening 21 is fixedly mounted. This sleeve 25 is made from a material which is more resistant to wear than the member 17. The two runs of a pull cord 20 are guided in the groove of the guide roll 22 and the ends of the pull cord preferably extend through the opening 21 in the sleeve 25 to the exterior of the unit so that the pull cord may be operated properly.

Referring now to FIGS. 9 and 10, there is shown therein another embodiment of invention according to which the elongated channel of the invention is still provided with the fastening projections in the form of the flanges 3 and 4 which extend longitudinally along the channel fixed to the opposed side walls of the latter so as to cooperate in the above-described manner with the plurality of fastening means 9. The channel of FIGS. 9 and 10 includes an exterior track portion 26 along which slide members are adapted to glide, and in this case there are no pull cords and the articles such as curtains or the like which are supported from

such slide members are simply pulled by the user so as to arrange the curtains as desired the pulling on the curtains or the like moving the slide members along the track 26 in a well known manner. It will be noted that this track portion 26 of the embodiment of FIGS. 9 and 10 is located to one side of the channel of FIGS. 9 and 10, so that the base of the channel includes an elongated portion 27 of relatively large width which is located to one side of the track portion 26. In its upper face as viewed in FIG. 9, the base of the channel is formed with an elongated groove 29 for a purpose described below. The channel of FIGS. 9 and 10 is made of any suitable plastic or metal which can be bent by the user. Thus, if it is desired to extend the channel and the track portion 26 thereof along a path which is not straight, it is only necessary to cut away a substantially sector-shaped portion of the channel to the right of the track portion 26 thereof, as viewed in FIG. 9, and FIG. 10 shows an edge 28 of such a sector-shaped cutout portion. Once such a part of the channel of FIGS. 9 and 10 is cut away, it is possible to simply bend the channel so that track portion 26 thereof extends along a desired curved path, and the groove or longitudinal indentation 29 greatly facilitates the separation of the cut away part of the channel from the remainder of the latter. Thus, with the embodiment of FIGS. 9 and 10 it is a simple matter to arrange the channel so that it extends along any desired path.

It is apparent that the above-described structure of the invention can be applied to any desired wall, ceiling or the like for the purpose of supporting any curtains, panels, pictures, etc., for movement.

It will be understood that each of the elements described above, or two or more together, may also find a useful application in other types of track assemblies differing from the types described above.

While the invention has been illustrated and described as embodied in track assemblies for supporting draw curtains or the like, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. A track assembly for supporting draw curtains or the like comprising, in combination, an elongated channel having an exterior track portion and a pair of opposed side wall portions respectively terminating in free edges which are adapted to be located adjacent a surface of a support to which the channel is to be connected with the hollow interior thereof directed toward the support surface, said side wall portions of said channel fixedly carrying in the interior of said channel a pair of flanges, respectively, which extend longitudinally of said channel and having inner free edges spaced from each other in a direction transverse to the longitudinal direction of said channel a predetermined distance; and rotary rigid fastener means adapted to be turnably connected to said support at said surface thereof and having a pair of opposed wings having each a width smaller than said predetermined distance and having respectively free end edges spaced from each other a distance greater than said predetermined distance so that said wings are adapted to be turned from a position in which said wings are located between the inner free edges of said flanges to a position in which said wings engage said flanges

70 to the sides thereof which are directed away from said support surface upon manual turning of said rotary fastener means after the latter is fixed to said support and said fastener means including an operating portion fixed to said wings, and extending laterally beyond one of said side wall portions outwardly of said channel for manually turning said wings, so that said channel will then be held by said fastener means on said support with said fastener means housed, at least in part within said channel.

2. A track assembly comprising, in combination, an elongated channel having an exterior track portion and a pair of opposed side wall portions respectively terminating in free edges which are adapted to be located adjacent a surface of a support to which the channel is to be connected with the hollow interior thereof directed toward the support surface, said side wall portions of said channel respectively fixedly carrying in the interior of said channel a pair of flanges which extend longitudinally of said channel; and rotary fastener means adapted to be turnably connected to said support at said surface thereof to be located at least in part in said channel, said rotary fastener means having a pair of wings which are opposed to each other and which upon turning of said rotary fastener means by the operator become located against said flanges at the sides thereof which are directed away from the support surface so as to fix said channel to the latter, said channel being positioned, when fixed by said fastener means to said support, with one of said edges thereof in direct engagement with said surface of said support and with the other of said free edges spaced from said surface of said support, said rotary fastener means including an elongated lever extending outwardly beyond said channel across said other free edge thereof when said fastener means has not yet fixed said channel to said support and the operator turning said lever to turn said fastener means to a position fixing said channel to said support, said lever turning during rotation of said fastener means by the operator to a position located to a greater degree between said channel and support surface and said other free edge of said channel engaging said lever while said lever directly engages said support surface.

3. A track assembly for supporting draw curtains or the like comprising, in combination, an elongated channel having an exterior track portion and a pair of opposed side wall portions respectively terminating in free edges which are adapted to be located adjacent a surface of a support to which the channel is to be connected with the hollow interior thereof directed toward the support surface, said side wall portions fixedly carrying in the interior of said channel a pair of longitudinally extending flanges and having inner free edges spaced from each other in a direction transverse to the longitudinal direction of said channel a predetermined distance; and rotary rigid fastener means adapted to be turnably connected to said support at said surface thereof and including a pair of wings having each a width smaller than said predetermined distance and having respectively free end edges spaced from each other a distance greater than said predetermined distance so that said wings are adapted to be turned from a position in which said wings are located between the inner free edges of said flanges to a position in which said wings engage said flanges at the sides thereof which are directed away from said surface of said support upon manual turning of said fastener means after the latter is fixed to said support, said wings respectively forming parts of a pair of helices and said fastener means including an operating portion fixed to said wings and extending laterally beyond one of said side wall portions outwardly of said channel for manually turning said wings so that the continued turning of said fastener means causes said wings to act on said flanges to press said channel against said surface of said support, said fastener means being located

at least in part in said channel when the latter is connected by said fastener means to said support.

4. A track assembly for supporting draw curtains or the like comprising, in combination, an elongated channel having an exterior track portion and a pair of opposed side walls respectively terminating in free edges which are adapted to be located adjacent a surface of a support to which the channel is to be connected with the hollow interior thereof directed toward the support surface, at least one side wall portion fixedly carrying in the interior of said channel a projection, said channel having at least one open end; fastener means adapted to be movably connected to said support and said surface thereof and being manually movable to a position engaging said projection and thereby fastening 15 said channel to said support, said fastener means being housed at least in part in said channel when the latter is connected by said fastener means to said support; and an elongated extension strip having a profile corresponding to that of said channel and slidably telescoped in the latter through said open end thereof, said extension strip engaging said projection at the side of the latter which is directed away from the surface of 20 said support and said extension strip also engaging the base of the channel in the interior of the latter and said extension strip being adapted to engage said surface of said support, so that said extension strip is guided for movement longitudinally of said channel.

5. A track assembly for supporting draw curtains or the like comprising, in combination, an elongated channel having an exterior track portion and a pair of opposed side walls respectively terminating in free edges which are adapted to be located adjacent a surface of a support to which the channel is to be connected with the hollow interior thereof directed toward the support surface, at least one side wall portion fixedly carrying in the interior of said channel a projection, said channel having at least one open end; fastener means adapted to be movably connected to said support and said surface thereof and being manually movable to a position engaging said projection and thereby fastening 25

5
